CARPET CLEANER

Judson O. Jones, 17 Inglewood Drive,
Greenville, S.C. 29609

Filed Feb. 6, 1970, Ser. No. 21,314

Term of Patent 14 years

Int. Cl. D15—06

U.S. Cl. D49—11

Fig. 1.

Fig. 2.

FIG. 1 is a front perspective view of a carpet cleaner embodying my new design, and

FIG. 2 is a rear perspective view of the carpet cleaner in FIG. 1 further illustrating my new design.

The broken lines are for illustrative purposes only.
I claim:

The ornamental design for a carpet cleaner, substantially as shown and described.
